TURBINE APPARATUS

Eric Zetterquist, Drexel Hill, Pa., assignor to
Westinghouse Electric & Manufacturing Company,
East Pittsburgh, Pa., a corporation of
Pennsylvania

Application February 9, 1934, Serial No. 710,411

4 Claims. (Cl. 253—77)

My invention relates to blading for axial flow elastic-fluid turbines and more particularly to blading of the end-tightened type; that is, blading wherein the axial clearance may be varied by moving one of the relatively-rotating blade-carrying members axially with respect to the other blade-carrying member.

End-tightened blading in elastic-fluid turbines has the advantage of providing close working clearances during the normal operation of the turbine. However, in prior apparatus of this type, the advantage just mentioned has been offset to some extent by the detrimental effect of eddy currents in the main stream of axially flowing motive fluid. The eddy currents are caused by the motive fluid escaping through the close working clearances and around a row of blades from the high pressure side thereof and entering again the main stream at the low-pressure side of such row of blades at high velocities and in a direction transverse to the path of flow of the main stream.

It is an object of this invention to provide apparatus of this character wherein the aforementioned detrimental eddy currents are avoided.

A further and more specific object is to provide an improved form of axial clearance packing which is so constructed and arranged that the velocity of the motive fluid escaping therethrough is dissipated before such fluid reaches the low pressure side of the blade; and hence, such escaping motive fluid enters the main stream at the low pressure side of the blades without causing the aforementioned detrimental eddy currents.

According to my invention, I provide first and second relatively-rotating blade-carrying members, and at least two cooperating rows of blades through which the motive fluid flows successively with the pressure of the motive fluid being decreased as it flows through each row, a first of such rows being carried by the first blade-carrying member and a second of such rows being carried by the second blade-carrying member. A blade shroud is secured to each row of blades and each shroud and the opposing blade-carrying member are arranged with an annular space therebetween. A first means provides an axial packing clearance between the shroud of the first row of blades and the second member, and a second means provides an axial packing clearance between the second row of blades and the first blade-carrying member, and both of the axial packing clearance means are constructed and arranged to permit axial movement of the

first blade-carrying member relative to the second member to vary the packing clearance. The first and second axial packing clearance means are further constructed and arranged so that the velocity of motive fluid escaping therethrough from the high pressure side is dissipated in the relatively large adjacent annular space, thus lowering the velocity of the escaping motive fluid and permitting such fluid to enter the main stream without eddying.

According to the specific embodiment of my invention shown on the accompanying drawing, one of the packing clearance means is in the form of an annular packing strip extending in an axial direction from the high pressure side of a row of blades and toward a blade-carrying member; and the other packing clearance means is in the form of an annular packing strip having at least the outer portions thereof extending in a direction opposite to the strip of the first-mentioned packing clearance means and cooperating with an annular shoulder carried by the opposing blade-carrying member to direct the escaping motive fluid radially against the blade shroud, thus aiding in reducing the velocity of the escaping motive fluid.

These and other objects are effected by my invention, as will be apparent from the following description and claims taken in connection with the accompanying drawing, forming a part of this application, in which:

The single figure on the drawing is a fragmentary transverse section through a portion of a turbine in which my invention is embodied.

Referring now in detail to the construction illustrated, it will be observed that I have shown a portion of an axial-flow elastic-fluid turbine including two blade-carrying members 10 and 11, respectively. Insofar as my invention is concerned, either of these members may be considered as the rotor and the other the cylinder. However, for the purpose of description, I will call the member 10 the rotor or spindle of the turbine and the member 11 the cylinder thereof.

Secured to the rotor 10 and extending radially therefrom are a plurality of spaced rows of reaction blades identified by the reference characters 12, 13, and 14, respectively. Arranged in cooperative relationship with the rotating blades are a series of stationary blades indicated by the reference numerals 15, and 16, respectively; the stationary blades being carried by the cylinder 11, as shown. The elastic fluid, for example, steam, flows in an axial direction successively through the turbine blades as indicated by the arrow; and

as the steam flows through each row of blades, the pressure thereof is reduced, as is well known in the art.

An annular shroud 17 is secured to each row 5 of rotating blades, and an axially-extending annular packing strip 18 is carried by each shroud 17 and extends toward the opposing cylinder 11 to provide an axial packing clearance 19 for the purpose of restricting the escape of steam around

10 the ends of the blades. Likewise, an annular shroud 20 is secured to each row of stationary blades and each shroud 20 is provided with an annular packing strip 21, the outer end 22 of which extends axially and in a direction opposite 15 to that of the strip 18 and cooperates with an annular shoulder 23 on the rotor 10 to provide a packing clearance 24 which serves to restrict the escape of steam around the ends of the stationary blades.

20 It will be observed that the packing strip 18 extends axially from the outer high pressure edge of each row of moving blades. With such an arrangement, the velocity of the motive fluid escaping through the packing clearance 19 is substantially lowered, because the escaping fluid 25 enters a relatively large annular space 25 surrounding the tips of the moving blades before it enters the main stream of motive fluid at the low pressure side.

30 Likewise, the packing clearance 24 is also arranged adjacent the high pressure side of the stationary blades and, therefore, the velocity of motive fluid escaping therethrough is dissipated in the relatively larger space 26 surrounding each

35 row of stationary blades. A further feature of the construction of the packing clearance 24 is that the shoulder 23 and the outer end 22 of the packing strip 21 are so arranged that steam escaping through the clearance 24 is directed radially toward the shroud 20. On account of this 40 arrangement, the escaping motive fluid is caused to turn corners in the relatively large space 26 before reaching the main stream at the low pressure side of the blade, and, therefore, the velocity 45 of the escaping steam is further reduced.

It will also be observed that the outer end 22 50 of the packing strip 21 extends in a direction opposite to that of the packing strip 18. By reason of this construction, adjustment of the packing 55 clearances 19 and 24 may be had by an endwise movement of the rotor 10. That is to say, movement of the rotor in the direction of elastic fluid flow increases the packing clearance 19 and 24 and, conversely, movement of the rotor in the opposite direction decreases the packing clearances.

From the above description, it will be seen that I have provided a construction wherein the detrimental eddying effects caused by the high velocities of the escaping motive fluid are eliminated 60 and at the same time one wherein the packing clearances may be adjusted during normal turbine operation to reduce the amount of escaping motive fluid.

While I have shown my invention in but one form, it will be obvious to those skilled in the art that it is not so limited, but is susceptible of various changes and modifications without departing from the spirit thereof, and I desire, therefore, that only such limitations shall be placed thereupon as are imposed by the prior art or as are specifically set forth in the appended claims.

What I claim is:

1. In a turbine, a rotor and a stator having spaced radial faces, stationary and moving rows 10 of blades carried by the stator and by the rotor, respectively, shrouds carried by the stationary and moving rows of blades, and cylindrical packing 15 elements connected to the high pressure sides of the shrouds and cooperating with the radial faces to define relatively close clearances, the cylindrical packing elements connected to the shrouds of the moving rows of blades extending forwardly of the high pressure sides of the latter to cooperate with radial faces on the stator and the cylindrical packing elements joined to the shrouds of the stationary rows of blades extending rearwardly from the high pressure sides 20 of the latter to cooperate with radial faces on the rotor.

2. The combination as claimed in claim 1 25 wherein the stator and the rotor are provided with circumferential spaces arranged outwardly of the moving blade shrouds and inwardly of the stationary blade shrouds and into which steam 30 escaping from between the fine clearances is discharged.

3. In a turbine, a rotor and a stator having spaced radial faces, stationary and moving rows 35 of blades carried by the stator and by the rotor, respectively, shrouds carried by the moving rows of blades and extending forwardly of the high pressure sides thereof to define close clearances with respect to the stator radial faces, and shrouds carried by the stationary blades and having portions springing from the high pressure sides thereof and extending outwardly and rearwardly to define relatively close clearances with 40 respect to said rotor radial faces.

4. In a turbine, a rotor and a stator having spaced radial faces, stationary and moving rows 45 of blades carried by the stator and by the rotor, respectively, shrouds carried by the moving rows of blades and extending forwardly of the high pressure sides thereof to define relatively close clearances with respect to the stator radial faces, shrouds carried by the stationary blades, and annular packing members including inner radial 50 portions joined to the high pressure sides of the last-named shrouds and cylindrical portions joined to and extending rearwardly from said radial portions to define relatively close clearances 55 with respect to said rotor radial faces.
